COIN CONTROLLED MECHANISM

Filed Nov. 3, 1925

INVENTOR,

R. DUBIN.

ATTORNEY,

Sterling P. Buck.

UNITED STATES PATENT OFFICE.

RAYMOND DUBIN, OF BALTIMORE, MARYLAND.

COIN-CONTROLLED MECHANISM.

Application filed November 3, 1925. Serial No. 66,566.

This invention relates to coin controlled mechanisms, and especially to such mechanism that is operable to eject articles or packages such as individual sticks of chewing gum or packages of the same or of other material.

It has been found that vending machines of the coin-controlled or "check-controlled" type often fail to properly operate because the coin or check is gripped between two parts such as the article ejector and the operating pusher and remains so gripped during the returning movement of the parts that engage with the coin or check. When the coin is so returned, instead of being dropped or deposited in the coin-receptacle, it enables the purchaser to obtain two or more packages of the vended material instead of only the one to which he or she is entitled. Different kinds of devices have been invented for forcing the gripped coin into the coin-receptacle, but such devices offer a resistance to the continued operating movement of the operating pusher, so the purchaser is likely to think the vending operation is over before it actually is over, and will allow the operating pusher to return before the coin is released from the grip of the vending pusher and operating pusher.

One object of this invention is to overcome the disadvantages explained in the foregoing, and to provide a very simple and comparatively inexpensive and thoroughly practical and effective coin controlled device for the purpose explained.

Other objects and important features will be seen in the following details of description, in connection with the accompanying drawings in which,—

Fig. 1 is a sectional view through a simple form of vending machine, showing my improved coin controlled mechanism in top plan.

Fig. 2 is an enlarged detail view showing the inner end of the operating pusher in horizontal section and in side elevation.

Referring to these drawings in detail, in which similar reference characters correspond to similar parts in the several views, the invention and its adjuncts are described as follows:

The casing or main body of the vending machine includes an operating chamber having a floor 5; a merchandise-chamber having a floor 6; a coin-receiving chamber

having a coin-inlet 7; and a merchandise receiving and dispensing chamber having an opening or inlet 8 through which the chewing gum or other merchandise falls, 60 into reach of the purchaser, when the vending pusher has pushed it from the floor 6 into the hole 8. The floor 5 has also a hole 9 therethrough, and this hole may communicate with the vending chamber (seen 65 partly at 8), so the machine can not be operated by a coin or check that is smaller than the diameter of the hole 9, but such small coin will drop through the hole 9 and be returned to the vending chamber 70 where it can be regained by the purchaser or person who put it into the machine.

The coin or check is here shown at C, and it is seen that the hole 9 does not permit it to pass through, because it is of the size 75 intended to control the vending machine, but the hole 7 is large enough to permit such coin to drop therethrough into the coin-receptacle.

The vending pusher 10 has relatively 80 broad pushing heads 11 that serve the dual purpose of pushing the merchandise from the floor 6 and limiting the forward movement of the vending pusher, that is, its movement towards the front of the machine, 85 because these heads 11 normally abut against two guiding members or staples 12 that straddle the narrow parallel parts of the member 10. Springs 13 are secured to the member 10 and to the floor 5, and these pull and normally hold the member 10 forward. An arcuate recess is formed in the member 10, and this recess is only large enough to receive, without binding or gripping, the coins of the size to control 90 the vending machine. The wall of this arcuate recess terminates in two sharp-edged shoulders 15 having their sharp edges very near to the controlling coin or check when the latter is in the recess 14. 100 The controlling coin has a part of its periphery between the shoulders 15 for a purpose that is explained hereinafter.

The operating pusher comprises a pushing bar 16 and two pawls 17 which latter are pivoted at 18, preferably extending from a slot 19, and are of such shape that they can not swing inward or towards one another from the positions shown in Figs. 1 and 2, but can swing outward or away 110 from one another when unobstructed. They may be held in the normal position (shown)

either by suitable springs (not shown) or by the two studs or stops 20, so they will pass through the space between the shoulders 15 if the operating pusher is pushed in when no coin or check is in the recess 14, and in such case, no vending will take place. A spring 21 is provided to return the operating pusher to its normal forward position, and in thus returning it, cooperates with the studs 20 for returning the pawls to normal position if they have been spread apart. A slot 22 and a pin or guiding element 23 cooperate with a slot 24, of the main body, to keep the operating pusher in its proper path of movement.

The operation of the device is as follows:

Assuming that a stack or tier of packages are on the floor 6, that a proper sized coin or check C is placed in the recess 14 (by any appropriate chute or other means), and that the operating pusher is pushed in: The circular edge of the coin immediately tends to deflect the pawls toward the shoulders 15, but the studs or pins 20 prevent such deflection until the pawls have moved rearward a slight distance; but when the pivots 18 pass between the studs or pins 20, the pawls are then free to be deflected by the circular edge of the coin, and when so deflected, they move into engagement with the shoulders 15 and out of engagement with the coin, thus releasing the latter so it is free to fall through the opening 7 soon as it passes far enough over said opening. The pawls retain their engagement with the respective shoulders 15 while the operating pusher and vending pusher continue their rearward movement until the package is pushed from the floor 6 and falls into the vending opening 8; but the pins or studs 20 disengage the pawls 17 from the shoulders 15 when the spring 21 returns the operating pusher to its normal forward position.

I do not intend to limit my patent protection to the exact construction and arrangement here shown, but the inventive ideas contemplate numerous forms and arrangements within the scope of the invention as implied and claimed.

What I claim as my invention is:

1. The combination of a member movable to dislodge an article of merchandise and provided with a recess to receive a coin or check, and also provided with a shoulder adjacent to said recess, and an operating member movable into said recess when no coin is in the said recess, said operating member being provided with means to engage with a coin when in said recess and to be deflected by the coin out of engagement with the coin and into engagement with said shoulder for effecting an operating movement of the first said member.

2. The combination of a member movable to dislodge an article and provided with a recess to receive a coin or the like and having shoulders between which the coin extends when in said recess, and an operating member movable into said recess when no coin is therein, said operating member including pawls operable by a coin in the recess so as to disengage them from the coin and operatively engage them with said shoulders and thus render the operating member effective to cause the first said member to dislodge said article.

3. The combination of a member movable to dislodge an article and provided with a recess to receive a coin or the like and having shoulders between which the coin extends when in said recess, an operating member movable into said recess when no coin is therein, said operating member including pawls operable by a coin in the recess so as to disengage them from the coin and operatively engage them with said shoulders and thus render the operating member effective to cause the first said member to dislodge said article, and means to disengage said pawls from said shoulders and hold them in position to pass between the shoulders when no coin is in said recess.

4. In a device of the character described, the combination of a member movable to dislodge an article and provided with a recess to receive a coin or the like and having sharp-edged shoulders adapted to be very close to a controlling coin or the like when such coin is in said recess, said member being provided with means to guide it in its forward and rearward movements, a floor supporting said member and its guiding means, said floor having a relatively large hole and a relatively small hole therethrough, the margin of the latter supporting the proper sized controlling coins or checks but permitting smaller coins or checks to drop therethrough, the larger sized hole being adapted to permit the proper sized controlling coins to drop therethrough, an operating pusher provided with pawls normally in position to pass between said shoulders when no coin is in said recess, said pawls being operable by a coin in said recess so as to engage them with said shoulders while disengaging them from the controlling coin, studs secured to said floor in position to hold the pawls in their normal position, resilient means to return the operating pusher to its normal position and to cooperate with said studs for returning said pawls to their normal position, and resilient means to return the first said member to its normal position.

In testimony whereof I affix my signature.

RAYMOND DUBIN.
